(57) **CLAIM**

The ornamental design for a touch-sensitive linear adjustment switch, as shown and described.

DESCRIPTION

FIG. 1 is a perspective view of a touch-sensitive linear adjustment switch showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom perspective view thereof.

The claimed touch-sensitive linear adjustment switch is typically mounted to a flat surface when in use.
